UNITED STATES PATENT OFFICE.

WILLIAM H. WILDER AND FRED E. WHITE, OF GARDNER, MASSACHUSETTS, ASSIGNEES
TO CENTRAL OIL & GAS STOVE COMPANY, A CORPORATION OF MASSACHUSETTS.

DESIGN FOR AN OVEN.

42,659.

Specification for Design.

Patented June 18, 1912.

Application filed February 19, 1912. Serial No. 678,745. Term of patent 14 years.

To all whom it may concern:

Be it known that we, WILLIAM H. WILDER and FRED E. WHITE, citizens of the United States, residing at Gardner, Massachusetts, have invented a new and original and ornamental Design for an Oven, of which the following is a specification, reference being had to the accompanying drawing, forming part thereof.

Figure 1 is a front elevation and Fig. 2

is an end elevation of an oven showing our new design.

We claim:

The ornamental design for an oven, as shown.

WILLIAM H. WILDER.
FRED E. WHITE.

Witnesses:

SOLON WILDER,
H. D. BURNHAM.
